CLAIM

I claim the ornamental design for a fixing assembly, as shown and described.

DESCRIPTION

FIG. 1 is a front elevational view of the fixing assembly showing our new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a first perspective view thereof; and,

FIG. 8 is a second perspective view thereof.

1 Claim, 3 Drawing Sheets
